UNITED STATES PATENT OFFICE.

HERMAN ROSSWINKLE, OF MARSHFIELD, OREGON.

HEADREST.

Application filed March 17, 1926. Serial No. 95,352.

This invention relates to a new and improved head rest for use upon chairs of various characters, automobile seats, and other articles of furniture where such devices are found desirable.

My principal object is to generally improve upon inventions of this class by providing one of exceeding simplicity and durability which is such in construction as to reduce the cost of manufacture to a minimum, to make for ease in construction, and to provide an altogether practical and convenient article such as will effectively serve the purpose for which it is designed.

Other objects, features of construction, and advantages, will become apparent from the following description and drawings.

In the accompanying drawing forming a part of this application and in which like numerals are employed to designate like parts throughout the same:

Figure 1 is a rear elevation of a headrest constructed in accordance with the present invention.

Figure 2 is a central vertical section through the same showing the construction more plainly.

Referring to the drawing in detail, the reference character 1 designates an annular pneumatic cushion adapted to be filled with air through a suitable air valve 2. Formed integral with this annular cushion and preferably in the same piece of material is a circular center 3 forming a flexible web against which the head of the user is adapted to be placed. The device also includes a hanger strap 4 of suitable form which is permanently attached to the rear side of the cushion and center to properly suspend the device from an appropriate support. This hanger strap is formed with button holes 5 whereby it may be buttoned upon the chair, seat back, or other device with which the invention is associated.

From the foregoing it is obvious that by means of the hanger 4, the device is attached to the back of the chair, seat, or other article of furniture with which it is to be associated. The annular cushion 1 rests against the chair back and the lower portion thereof forms somewhat of a rest for the neck of the user, while the central circular portion 3 constitutes a rest for the back of the head. This is quite flexible and makes an exceedingly comfortable rest for the head. The entire device may be made of rubber if desired.

It is believed that the use and construction of the device will be clear to persons familiar with articles of this class and a more lengthy description is therefore deemed unnecessary.

Changes in shape and size coming within the field of invention claimed may be resorted to if desired.

Having thus described the invention, what I claim as new and desire to secure by Letters Patent is:—

As a new article of manufacture, a head rest of the class described comprising a hollow annular cushion adapted to be inflated with air, said cushion being provided with a filler valve located on the exterior of the outer periphery of the cushion, a circular diaphragm formed integral with the inner peripheral portion of the cushion, said diaphragm being of double thickness, and a relatively narrow hanger strap attached at the point of connection of the diaphragm and cushion, said strap being provided with a single row of longitudinally spaced suspending apertures, and said strap being located to cooperate in shielding said valve.

In testimony whereof I affix my signature.

HERMAN ROSSWINKLE.
